UNITED STATES PATENT OFFICE.

WILLIAM W. SHIRLEY, OF NEW ORLEANS, LOUISIANA.

WIRE-BENDING MACHINE.

1,079,890.

Specification of Letters Patent. Patented Nov. 25, 1913.

Application filed February 27, 1913. Serial No. 751,121.

To all whom it may concern:

Be it known that I, WILLIAM W. SHIRLEY, a citizen of the United States, residing at New Orleans, in the parish of Orleans and 5 State of Louisiana, have invented certain new and useful Improvements in Wire-Bending Machines, of which the following is a specification.

This invention has reference to wire-bending machines, and especially to machines for bending wire strips to form plate and lid lifting implements of the general type shown and described in my prior Patent, No. 972,983, issued October 18, 1910.

15 It proposes certain hereinafter described improvements in or relating to the devices employed for shaping the lifting hooks provided upon the ends of the handles included in such implements, whereby both hooks 20 may be bent into shape at the same time, and by a single movement of the operating member of the machine.

Also, it comprehends improved devices for holding the implement in place upon the 25 work table or like support during the aforesaid shaping operation, these holding devices being so constructed and arranged as to admit of their being readily disengaged from the implement at the conclusion of the 30 operation.

An embodiment of the invention is illustrated in the accompanying drawing, whereof—

Figure 1 is a perspective view of the complete machine, showing the lifter in dotted lines, prior to the above-mentioned shaping operation; Fig. 2 is an enlarged, fragmental longitudinal vertical section; Figs. 3 and 4 are transverse vertical sections taken, respectively, on the lines 3—3 and 4—4 of Fig. 2; and Fig. 5 is a fragmental perspective view of the completed lifter.

In said drawing, 7 indicates, generally, the work table or support whereon the various operations subsequently described, take place, and 8 an upright on whose top said support is mounted and to which it is secured by a bolt 9. The parts 7 and 8 may have any desired size, and the former is 45 preferably constituted by a narrow, bar-like metal member provided with an opening through which bolt 9 passes, the lower end of the bolt extending into an opening 50 formed in the upright, to permit the application of the fastening nut 11.

One end of the work support is extended

downwardly at an angle, as indicated by the numeral 12, this inclined portion being provided with a series of upstanding pins 13 and, also, with a series of cross-pins 14, both of which sets of pins are initially used in forming the preliminary bends in the implement. As these preliminary steps are not comprehended in the invention proper, which relates primarily to the shaping of the hereinafter described lifting hooks, they need no specific description, nor is it deemed necessary to describe the implement itself in detail, as reference may be had to my prior patent, above identified, for a complete understanding thereof. It is sufficient, therefore, to state that the implement comprises upper and lower handle members 15 and 16 having a pivotal connection with each other at the points 17, 17 and provided with terminal, pan-engaging devices 18 and 19. In addition to these devices, hooks 20 and 21 are provided upon the outer ends of the handles proper, which hooks are initially in the form of longitudinal loops 80 that are subsequently bent into the proper shapes by the operating member herein-after described. In the completed implement the hook 20 on the upper handle 15 projects upwardly and outwardly therefrom 85 at a suitable angle, and is designed for reception in the usual socket provided in the stove lid, while the hook 21 on the lower handle 16 is inclined inwardly and downwardly, and is to be engaged with the rim 90 of a pie plate or the like.

At the opposite end from the extension 12, the work support is provided with a pair of upstanding spaced lugs 22 connected by a pair of cross-bars 23 and 24. The bar 23 95 serves as a fulcrum for the operating member 25 which is here shown as constituted by a lever provided with an upwardly curved head 26 having a depending arm 27 extending from the base thereof, (i. e., at 100 the point where said head joins the stem or body of the lever), said arm being arranged divergently from said head. In said head there is provided a longitudinal slot 28 having a slightly arcuate formation, through which slot bar 23 extends, the arrangement being such, therefore, that when the lever is operated a longitudinal movement thereof, as well as a rocking movement is permitted, which serves to relieve the strain upon said 110 bar. The other bar 24 is disposed in front of and slightly below bar 23, and adjacent

an opening or socket 29 having substantially the shape of an inverted cone, its rear wall having a much less abrupt slope than its front wall. The arm 27 is designed to enter this socket, when the lever is depressed, so as to engage the hook 21 which is supported upon the aforesaid rear wall thereof, the hook 20 projecting upwardly and rearwardly beneath bar 24, as depicted in dotted lines in Fig. 1.

In addition to their preliminary use in connection with the initial bending steps, the pins 14 are utilized to retain the partially completed implement in place upon the support 7 during the shaping of the hooks 20 and 21. In performing this latter function, they are assisted by the pins 14, and, also, by supplemental retaining devices 30, 31 and 32. The device 30 is located between the front and rear devices 31 and 32 and is preferably in the form of a screw which is set into the work support toward the extension end 12 thereof, the head of said screw overhanging and engaging the arms of the upper handle 15 adjacent the point where they are bent to form the devices 18, at which point they are also engaged by the retaining device 31. Both retaining devices 31 and 32 are of the disappearing type; that is to say, they are movable into and out of operative position to engage or release the implement, and, when in inoperative position, are disposed within the work support. They are here shown as constituted by U-shaped pins whose arms work in pairs of vertical passages formed through the support, and whose connecting portions or bases are pivoted to the outer ends of a pair of small levers 33 and 34 which are centrally fulcrumed in depending brackets 35 carried by said support. The inner or operating portions of these levers project into a horizontal passage 36 formed in the top of standard 8 and intersected at right-angles by a pair of finger openings 37 which are formed transversely through the standard top to provide access to said levers. The passages wherein the arms of the rear device 32 work open through the side walls of socket 29 and in close proximity to the rear or supporting wall thereof, as depicted in Fig. 2. In their lowered or inoperative position, the terminals of these arms lie flush with the upper face of the work support. When the initial bending and shaping steps have been completed and the implement is placed upon the work support in the manner already described, the movable retaining devices 31 and 32, which have previously been raised by manipulation of the levers 33 and 34, will respectively engage the arms of handle 15, at the points where the latter and the devices 18 meet, and the arms of both handles at the junc-

tion of the same and the hooks 20 and 21, the arms of the rear device 32 extending between the handle arms, as shown. In this way, the two handle members, which are then superposed, are held against all possible endwise, sidewise and vertical displacement, as will be understood. Lever 25 is then swung to the right and downwardly, during which movement its head 26 will engage hook 20, which projects upwardly toward it, and will bend the said hook upwardly and forwardly over bar 24, while its arm 27 will enter socket 29 and bend hook 21 downwardly and inwardly in the desired manner. At the completion of this operation, the retaining devices 31 and 32 are lowered to disengage them from the finished implement, whereupon the latter may be readily removed.

Having described my invention, I claim:

1. In a wire-bending machine, the combination, with a work support provided with a work-engaging cross-bar and with a vertical socket adjacent the same; of a lever fulcrumed on said support and having a curved head coöperative with said bar to bend a portion of the work thereover, and a depending arm adapted to enter said socket to bend another portion of the work downwardly therein, when said lever is swung toward said support; and work-retaining devices carried by said support.

2. In a work-bending machine, the combination, with an apertured work support provided with a work-engaging cross-bar, and with a vertical socket adjacent the same; of a lever fulcrumed on said support and having a curved head coöperative with said bar to bend a portion of the work thereover, and a depending arm adapted to enter said socket to bend another portion of the work downwardly therein, when said lever is swung toward said support; a work-retaining device movable through the aperture in said support into and out of position to engage the work; and means for operating said device.

3. In a wire-bending machine, the combination, with a work support and a bending lever fulcrumed thereon, said support being formed with a pair of parallel passages extending transversely therethrough; of a U-shaped work retaining device having its arms working through said passages; and an operating lever connected to the base of said device for moving the latter into and out of position to engage the work.

4. In a wire-bending machine, the combination, with a work support and a bending lever fulcrumed thereon, said support being provided adjacent its ends with pairs of parallel passages extending transversely therethrough; of a standard whereon said support is mounted formed at its top with a

horizontal passage parallel with said support, and with a pair of finger openings intersecting said passage substantially at right angles; a U-shaped work-retaining device 5 having its arms movable through each pair of passages; and a lever fulcrumed on said support adjacent each retaining device and connected to the latter at its outer end, the inner ends of said levers extending in opposite directions into the passage in said 10 standard and terminating adjacent said finger openings.

5. In a wire-bending machine, the combination, with a work support provided 15 with a vertical socket and with a pair of parallel passages extending transversely therethrough and located adjacent said

socket; of a lever fulcrumed on said support and having a bending head provided with an arm adapted to enter said socket 20 when said lever is swung toward said support; a U-shaped work-retaining device having its arms movable through said passages; and a lever fulcrumed on said support and connected with the base of said 25 work-retaining device for moving the latter into and out of operative position.

In testimony whereof I have hereunto set my hand in presence of two subscribing witnesses.

WILLIAM W. SHIRLEY.
